(57) CLAIM

The ornamental design for a bowl, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, right perspective view of a first embodiment of a bowl showing our new design;

FIG. 2 is a front view thereof, wherein the rear view is a mirror image of FIG. 2;

FIG. 3 is a right side view thereof, wherein the left side view is a mirror image of FIG. 3;

FIG. 4 is a top view thereof;

FIG. 5 is a bottom view thereof;

FIG. 6 is a top, front, right perspective view of a second embodiment of the bowl of FIGS. 1-5 showing our new design;

FIG. 7 is a front view thereof, wherein the rear view is a mirror image of FIG. 7;

FIG. 8 is a right side view thereof, wherein the left side view is a mirror image of FIG. 8;

FIG. 9 is a top view thereof;

FIG. 10 is a bottom view thereof;

FIG. 11 is a top, front, right perspective view of a third embodiment of the bowl of FIGS. 1-5 showing our new design;

FIG. 12 is a front view thereof, wherein the rear view is a mirror image of FIG. 12;

FIG. 13 is a right side view thereof, wherein the left side view is a mirror image of FIG. 13;

FIG. 14 is a top view thereof;

FIG. 15 is a bottom view thereof;

FIG. **16** is a top, front, right perspective view of a fourth embodiment of the bowl of FIGS. **1-5** showing our new design;

FIG. **17** is a front view thereof, wherein the rear view is a mirror image of FIG. **17**;

FIG. **18** is a right side view thereof, wherein the left side view is a mirror image of FIG. **18**;

FIG. **19** is a top view thereof; and,

FIG. **20** is a bottom view thereof.

The broken lines depicting the remainder of the bowl show features that form no part of the claimed design. The contrast in shading represents a contrast in appearance only and does not represent any particular color, materials, texture, or finish.
